UNITED STATES PATENT OFFICE.

CHARLES FOX, OF NEW YORK, N. Y., ASSIGNOR TO LEO SCHLESINGER, OF
NEW YORK, N. Y.

DESIGN FOR A TRAY.

● **40,590.**

Specification for Design.

Patented Mar. 29, 1910.

Application filed January 27, 1910. Serial No. 540,461. Term of patent 3½ years.

To all whom it may concern:

Be it known that I, CHARLES FOX, a citizen of the United States, residing in the city of New York, in the borough of Brooklyn, county of Kings, and State of New York, have invented a new, original, and ornamental Design for Trays, of which the following is a specification, reference being had to the accompanying drawing, forming a part hereof.

The figure is a plan view of a tray, showing my new design.

I claim;

The ornamental design for a tray, as shown.

CHARLES FOX.
